UNITED STATES PATENT OFFICE.

MARTIN H. CRANE AND DANIEL M. JEWETT, OF CINCINNATI, OHIO, AS
SIGNORS TO THE CRANE & BREED MANUFACTURING COMPANY, OF
SAME PLACE.

COFFIN.

SPECIFICATION forming part of Letters Patent No. 351,742, dated November 2, 1886

Application filed August 27, 1886. Serial No. 211,965. (No model.)

To all whom it may concern:

Be it known that we, MARTIN H. CRANE and DANIEL M. JEWETT, citizens of the United States, residing at Cincinnati, in the county of 5 Hamilton and State of Ohio, have invented certain new and useful Improvements in Coffins, of which the following is a full, clear, and exact description, reference being had to the accompanying drawings, forming part of this 10 specification.

Our invention relates to improvements in coffins of that class known as "metallic caskets," which are intended to be perfectly airtight, and which can be hermetically sealed.

15 It has for its object the improvement in construction of this class of coffins, whereby the same, while light, are kept perfectly stiff and strong.

The novelty of the invention will be herein 20 set forth, and specifically pointed out in the claims.

In the accompanying drawings, Figure 1 is a longitudinal central section in elevation of our improved coffin. Fig. 2 is a sectional detail through the flange, showing its method of attachment to the upper edge of the body. Fig. 3 is a sectional detail showing one of the handle-sockets and the manner of securing the wooden lining. Fig. 4 is a sectional detail 25 showing the manner of securing the metal body to the wooden bottom. Fig. 5 is a sectional detail representing a modification in the construction of the bottom. Fig. 6 is a sectional end elevation through the dotted line 30 *x x* of Fig. 1.

The same letters of reference are used to indicate identical parts in all the figures.

The body *A* of the coffin is of sheet metal, made comparatively light, and intended to be 40 stiffened and strengthened by interior wooden linings *B* on each side, and an exterior wooden bottom, *C*. At the upper edge of the body and extending around, the coffin is the flange *D*, to which the lid (not here shown) is to be 45 fitted and hermetically secured. To secure this flange, which is usually of cast or malleable metal, to the upper edge of the body, we provide a strip of tin or zinc, *a*, which, inserted securely in a notch in the inner side of 50 the flange, preferably when the same is cast,

is bent down and confines the upper edge of the body between itself and the flange, as shown in Fig. 2. A tight joint is then effected by solder.

The wooden linings *B* extend from the top 55 to the bottom of the body and along the straight sides of the same up to the curves at each end. To hold these linings in place and to secure them firmly to the sides of the body, we employ socketed lugs *b*, which, soldered or otherwise tightly secured to the body, extend through perforations in the wooden lining and have retaining-washers *c* soldered upon their inner ends. These lugs, in addition to serving to secure the wooden linings *B*, also 60 serve as sockets, into which the handles for carrying the casket (not here shown) are screwed. To further hold the linings *B* in place and to secure them to the body, top strips, *d*, and bottom strips, *e*, are employed. 70 Of these the former, soldered to the inner side of the flange *D* at intervals, are bent over the top of the linings *B*, and are secured thereto by tacks or small screws. The latter, *e*, are right-angular strips at intervals, whose horizontal sides are soldered to the bottom of the body, and whose vertical sides bear against the inner sides of the wooden linings. 75

E F are wooden lining-strips bent to fit the curves at the end and secured, the former at 80 the bottom and the latter at the top of the inner side of the body, and are held in place by soldered sheet-metal strips *f* and *g*, as shown.

The wooden bottom *C*, as shown in Fig. 1, may be of a single piece, with its projecting 85 edge formed into an ornamental molding; or, as seen in Fig. 5, where greater lightness is sought, it may be composed of two thin pieces, *h i*, secured by an interposed framing-piece, *j*, and with the molding *k* secured thereto as a 90 separate piece. To secure the casket upon this wooden bottom, ordinary wood-screws, *m*, Fig. 4, are employed, which are passed through the metal bottom of the body *A*, and have their heads covered by strips *n*, of tin or zinc, 95 which are soldered over them.

In this manner we produce a coffin which, of light and comparatively cheap construction, is perfectly strong, may be made very ornamental, and is entirely air-tight; and, 100

Having thus fully described our invention, we claim—

1. In a coffin, the combination, with the metallic body, of the wooden linings fitted to the inner sides thereof, extending from the top to the bottom of the body, and secured thereto by socketed lugs provided with retaining-washers, and serving as means for securing the handles, substantially as described.
2. The combination, with the metallic body A, of the flange D, united thereto by the strip

a, the wooden linings B, secured by the strips d and e and socketed handle-lugs b, the lining-strips E F, and bottom C, the parts constructed and united substantially in the manner and 15 for the purpose specified.

MARTIN H. CRANE.
DANIEL M. JEWETT.
